UNITED STATES PATENT OFFICE

2,028,492

CORE ADAPTER

Edwin W. Bebie, Hawthorne, N. J., assignor to
 International Paper Company, New York,
 N. Y., a corporation of New York

Application July 25, 1934, Serial No. 736,875

6 Claims. (Cl. 242—68)

My present invention relates to a core adapter whereby a standard type of capped core provided with means for driving engagement with a round shaft having a key thereon may be adapted 5 for engagement with a polygonal shaft. The type of standard core to which I refer is preferably made according to the disclosure of United States Patent #1,358,531 granted to Phillip T. Dodge.

The advantages to be derived from my invention are numerous, consisting in part in the ease 10 and simplicity of changing a core to meet the requirements of different machines. In the newsprint industry the ordinary winding shafts are round, heavy shafts having a keyway within 15 which a key may be placed, said key engaging in a keyway constructed in the core. The keyway in the core is usually formed in a metallic core cap mounted upon and protecting the end of the core. The core is usually made of tightly 20 wound paper or other light fibrous material. In other industries, notably the textile industry, the ordinary winding shaft is constructed with a square or other polygonal driving end, and the cores made for this trade are constructed with a 25 matching cap having a polygonal opening therethrough. The purpose of my invention is to enable the immediate and easy conversion of a single core to fit either type of driving shaft.

My invention consists in an integral adapting 30 insert which may be applied to or detached from a standard newsprint core. These adapters may be shipped with the core or separately therefrom. Each adapter may be re-used as many times as desired, and likewise the core may be shifted from 35 use with a round shaft to use with a polygonal shaft, and vice versa, as many times as desired without ruining the strength and rigidity of the core. This has a distinct advantage inasmuch as it has heretofore been necessary to construct a 40 distinct type of capped core for every type of driving shaft encountered, whereas by means of my invention a single type of core may be supplied to all users of cores together with adapters 45 so constructed as to meet peculiar demands.

Other advantages and objects of my invention will be apparent from the following specification taken in connection with the accompanying drawings wherein like numerals refer to like parts 50 throughout.

In the drawing Fig. 1 is a side view of an adapter embodying my invention;

Fig. 2 is an end elevation looking toward the right end of Fig. 1;

Fig. 3 is an end elevation of a capped core

having an adapter applied thereto and looking toward the left end of Fig. 1;

Fig. 4 is a cross section taken along line 4—4 of Fig. 3;

Fig. 5 is a partial section corresponding to 5 Fig. 4;

Fig. 6 is a partial elevation corresponding to Fig. 3; and

Fig. 7 is a section of Fig. 6 taken along the 10 line 7—7.

My adapter comprises a metallic element preferably formed by stamping the same from a single flat sheet of thin metal. The adapter 10 comprises a flanged cup-shaped member having a polygonal opening at its bottom. This member 15 has an external diameter such that it will fit snugly within a capped core. The core comprises a member 11 to which a cap has been applied, the cap preferably having an outer flange 12 pressed into the core flush with its outer surface. 20 An inner flange 13 is preferably seated upon the inner surface of the core 11. Flanges 12 and 13 are joined by a rim 14, making a solid reinforced tip for the core. The adapter is formed with a number of longitudinal, flaring cuts 15 extending 25 inwardly from its open or inner end, thus dividing the wall of the adapter into a plurality of sections which may be resiliently urged inwardly. The inner edge of the adapter is formed with a lip 16 extending outwardly substantially the 30 thickness of flange 13. By reason of the slits 15 the inner end of the adapter may be contracted so that it may be slid lengthwise into the core. The adapter will be held in the core by the lip 16 35 which snaps over the end edge of flange 13.

The core 11 is provided with a slot within which fits a boss or bulge in the inner flange 13 forming a metal keyway 19 which cooperates with the key on the driving or winding shaft, thereby preventing the cap from turning upon the core 40 and preventing the key from rupturing the core upon the application of sudden stresses. In order to lock the core adapter against rotative movement within the core cap and also to prevent it from being driven longitudinally of the core, a 45 tongue 20 is struck outward from the wall of the adapter and fits into the keyway 19 in the core cap. The tongue is preferably formed of a single piece struck outward to parallel the bottom of the adapter or of the flange 14. However, other types of tongue or tongues, such as the tongues 21 shown in Figs. 6 and 7, may be used and may possess greater resistance to shearing or bending forces. If a greater degree of 50 strength is required or desirable, the wall of the 55

adapter 10 and the inner flange 13 of the core cap may be formed with matching depressions 17 and 18, respectively. These depressions may be formed after the adapter is in position by 5 means of any well known pressing tool, or they may be pre-formed and snapped into position as the adapter is driven into the core. If these depressions are pre-formed, it will be appreciated that the tongue 20 or tongues 21 will cause their 10 alignment and ready engagement.

The bottom of the adapter is slit along radial lines extending outwardly toward the side walls, if desired the entire radius may be slit or a portion thereof may be slit in order that polygonal 15 openings of various dimensions may be formed. The triangular flaps 22 thus formed are bent into the adapter and are preferably laid back toward the wall thereof in order that the inner approach to the opening thus formed may have converging 20 guide members. This is preferable in order that a long core may be seated upon a long shaft by a simple sliding movement. The segments 23 left in the plane of the bottom of the adapter are strengthened by reason of the presence of the 25 triangular portions 22, thus forming a very rigid structure which is well braced and is not liable to be ruptured at any point. The opening illustrated is in the form of a square, but it is obvious that a hexagonal or any other polygonal opening 30 may be so formed.

It is obvious from the foregoing that the adapter is easily inserted, and when inserted is not likely to be displaced either longitudinally or rotatively. It is also obvious that a polygonal shaft may be 35 easily passed through the opening from within the core as well as from without, and it is also obvious that the adapter may be removed without difficulty. This latter feature enables the same capped core to be adapted for any standard or 40 unusual type, shape or size of driving shaft, and thus reduces the number of types of cores necessary to maintain in stock and simplifies the production thereof. By reason of my invention, the only variance in manufacturing machinery is in 45 respect to the dies for forming the adapter itself, rather than in respect to the machines used for applying different types of caps to the cores.

The foregoing is a preferred embodiment of my invention and I do not intend to be limited to the 50 details thereof. Other modifications, alterations and substitutions are within the scope of my invention as expressed in the following claims which are to be broadly construed.

What I claim is:

55 1. A core adapter comprising a cup-shaped member provided with means for engagement with a capped core whereby said adapter is prevented from moving longitudinally and rotatively relative to a core to which it has been applied, 60 the bottom wall of said adapter being provided with a polygonal opening.

2. A core adapter comprising a cup-shaped member provided with means for engagement with a capped core whereby said adapter is prevented from moving longitudinally and rotatively relative to a core to which it has been applied, 5 the bottom wall of said adapter being provided with a polygonal opening, and the side wall of said adapter being provided with a plurality of slits extending toward said bottom wall from the edge thereof. 10

3. A core adapter comprising a cup-shaped member provided with means for engagement with a capped core whereby said adapter is prevented from moving longitudinally and rotatively relative to a core to which it has been applied, 15 the bottom wall of said adapter being provided with a polygonal opening, and the side wall of said adapter being provided with a plurality of slits extending toward said bottom wall from the edge thereof and a lip at its edge. 20

4. A core adapter comprising a cup-shaped member provided with means for engagement with a capped core whereby said adapter is prevented from moving longitudinally and rotatively relative to a core to which it has been applied, 25 the bottom wall of said adapter being provided with a polygonal opening, said opening being formed by inwardly bent flaps cut in said bottom wall.

5. A core adapter comprising a cup-shaped member provided with means for engagement with a capped core whereby said adapter is prevented from moving longitudinally and rotatively relative to a core to which it has been applied, 35 said means comprising at least one external projection adapted to engage with suitable depressions in said capped core, and a flanged lip at its edge, the bottom wall of said adapter being provided with a polygonal opening formed by inwardly bent flaps cut in said bottom wall, and 40 the side wall of said adapter being provided with a plurality of slits extending towards said bottom wall from the edge thereof whereby the flanged lip may be contracted to fit within a bore of substantially the same diameter as the diameter of 45 the bottom wall.

6. In combination, a fibrous tubular core of the type provided with a flanged cap having a keyway formed therein, and a core adapter having a sliding engagement therewith, said core adapter 50 being provided with means to engage said keyway to prevent rotative movement thereof relative to said core, and being provided with means to prevent accidental displacement of said adapter from said core comprising projections at 55 its inner edge and a plurality of slits extending from its inner edge toward its outer edge, said adapter being provided with a polygonal opening in its bottom wall whereby said core may be operatively associated with a polygonal shaft. 60

EDWIN W. BEBIE.
